The ornamental design for a solar-powered outdoor light, as shown and described.

DESCRIPTION

FIG. 1 is a front elevational view of a solar-powered outdoor light embodying the new design, which is the same as the right side elevational view, the left side elevational view and the rear elevational view.

FIG. 2 is an enlarged view of the claimed design illustrated in FIG. 1.

FIG. 3 is an enlarged top plan view of the design depicted in FIG. 1; and,

FIG. 4 is an enlarged bottom plan view of the design depicted in FIG. 1.

The broken lines shown in the drawings are for illustrative purposes only and form no part of the claimed design.
